UNITED STATES PATENT OFFICE.

THOMAS C. WASHINGTON, OF BROOKLAND, DISTRICT OF COLUMBIA.

DESIGN FOR A PUZZLE-BOARD.

SPECIFICATION forming part of Design No. 35,764, dated February 18, 1902.

Application filed December 18, 1901. Serial No. 86,463. Term of patent 3½ years.

To all whom it may concern:

Be it known that I, THOMAS C. WASHINGTON, a citizen of the United States, residing at Brookland, in the District of Columbia, have 5 invented and produced a new and original Design for Puzzle-Boards; and I do declare the following to be a full, clear, and exact description of the same, reference being had to the accompanying drawings, forming a part thereof.

10 Figure 1 is a plan view of the puzzle-board. Fig. 2 is an edge view of the same.

The leading feature of my design consists of a puzzle-board having its upper surface formed with a central depression and two concentric depressions, the central and inner concentric depressions being connected by a single passage-way, the two concentric depressions being connected by a plurality of pas-

sage-ways curved in a direction radial to said concentric depressions.

In the drawings, 5 designates the puzzle-board; 6, the central depression; 7 and 8, the inner and outer concentric depressions, respectively; 9, the passage-way connecting the central depression and the inner concentric 25 depression, and 10 the curved passage-ways. The surface of the board is provided with a plurality of oppositely-disposed bust-portraits, as shown.

I claim—

The design for a puzzle-board, substantially as herein shown and described.

T. C. WASHINGTON.
